UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,569, dated August 21, 1894.

Application filed July 28, 1894. Serial No. 518,886. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornaments of the renaissance style, having a shield-like 10 form as represented in the accompanying drawing. The ornaments are arranged at regular distances apart and small leaf ornaments are placed at uniform distances apart 15 between the shield-like ornaments. The border or upper portion of the design is formed of similar shaped ornaments with branches of

leaves intertwined with said ornaments and connected by a heart-shaped ornament having branches of leaves extending from the bottom of said ornaments as shown in the drawing. 20

What I claim is—

1. The design for wall paper herein shown and described.
2. In the design for wall paper, the border herein shown and described. 25

Witness my hand this 26th day of July, 1894.

CHARLES BOOZE.
